CLAIM

The ornamental design for a holder for payment terminal, as shown and described.

DESCRIPTION

1.1 is a front perspective view of the holder for payment terminal showing my new design;

1.2 is a front elevation view thereof;

1.3 is a rear elevation view thereof;

1.4 is a left side elevation view thereof;

1.5 is a right side elevation view thereof;

1.6 is a top plan view thereof; and,

1.7 is a bottom plan view thereof.

The broken lines shown are included for the purpose of illustrating portions of the holder for payment terminal that form no part of the claim.

1 Claim, 7 Drawing Sheets(56)
